UNITED STATES PATENT OFFICE.

SAHATIEL G. MANDALIAN, OF NORTH ATTLEBORO, MASSACHUSETTS.

DESIGN FOR A METALLIC MESH FABRIC.

Application filed June 24, 1924. Serial No. 9,957. Term of patent 14 years.

To all whom it may concern:

Be it known that I, SAHATIEL G. MANDALIAN, a citizen of the United States, residing at North Attleboro, in the county of Bristol and State of Massachusetts, have invented a certain new, original, and ornamental Design for a Metallic Mesh Fabric, of which the following is a specification.

In the accompanying drawing which forms a part of this specification the figure

is a front view of a portion of metallic mesh fabric showing my new design.

The shaded portions shown in the drawing represent a contrasting color, which give to the same a mottled appearance.

I claim:—

The ornamental design for a metallic mesh fabric, as shown.

SAHATIEL G. MANDALIAN.
